UNITED STATES PATENT OFFICE.

JOSEPH C. BONNER, OF TOLEDO, OHIO, ASSIGNOR OF ONE-HALF TO JOHN AMES, JR., OF SAME PLACE.

INVOICE-BLANK.

SPECIFICATION forming part of Letters Patent No. 465,336, dated December 15, 1891.

Application filed September 9, 1891. Serial No. 405,242. (No model.)

To all whom it may concern:

Be it known that I, JOSEPH C. BONNER, of the city of Toledo, county of Lucas, and State of Ohio, have invented a certain new and useful Invoice-Blank, of which the following is a specification, reference being had to the accompanying drawings.

The object of my invention is to produce an invoice-blank by which duplicate copies of so much of an invoice as it is desirable to duplicate may be made.

In shipping goods from one commercial house to another—as, for instance, from a manufacturer to a large wholesale pur-
15 chaser—the purchaser usually requires two separate invoices. One of them should be in the nature of a bill setting forth the amount of goods shipped and their price. The purpose of this is to advise the purchaser of the ship-
20 ment and the amount charged against him on the order. The other invoice or duplicate invoice (although it is customary in practice to mark each of the invoices “original” or “du-25 plicate”) is provided, in order that the purchaser may have a checking-slip for the receiving-clerk. On this duplicate it is desirable that no indication should be given of the price paid for the goods. The labor of preparing duplicate invoices is in a large 30 business considerable. By my invention I make one writing produce a required number of duplicate invoices, only one of which contains the price paid for the goods, and thereby effect a great saving of time and labor.

35 In the accompanying drawings, Figure 1 illustrates a pair of invoices prepared according to my invention, and Figs. 2, 3, and 4 illustrate different views of three sheets similarly prepared.

40 Referring to the letters on the drawings, A indicates an original invoice, or invoice adapted to show the price paid for goods. It may be made of paper and have the usual printing—such, for instance, as the date and place, 45 name of the buyer, and name of the seller.

B indicates a duplicate invoice which is shorter than the original, but is long enough to contain all matter descriptive of the order—such, for instance, as the name of the 50 buyer and the amount and quality of the goods, as illustrated in the drawings. These invoices are united at one end, where they may be folded or perforated, as illustrated at C in the drawings, for convenience of separation, or they may be bound together in a book.

In use the sheets A B, &c., are laid together, the one above the other, to constitute one complete invoice-blank. A statement or invoice is then written upon the top or largest sheet. At the same time provision is made for duplicating part of the statement on the smaller sheet or sheets lying underneath. For instance, if the invoice is made out on a typewriter, the duplicate can be copied by the use of carbon-paper coextensive with sheet B, or copying-paper may be used when the order is written in ink, or any suitable means of duplication may be employed.

By the use of blanks of this kind it is not necessary to give attention to writing but the one order, because so much of the order is duplicated on the blank B as it is desirable for that blank to contain and nothing more.

If a greater number of the shorter blanks is desired to be made at the same time with the invoice, another blank, as illustrated in Fig. 2 of the drawings, may be united to the end of the blank B and folded underneath and the process of duplication repeated with respect to the third as with the second invoice. The larger invoice may of course, if desirable, be duplicated in like manner.

I am aware that it is old to arrange together sheets of the same size to be laid one upon the other by folding or otherwise for the purpose of duplicating a writing, and I do not claim the same.

What I claim is—

An invoice-blank consisting of the combination of a plurality of sheets, one of which is large enough to contain a full statement of goods and prices, and the remainder being of smaller dimensions, to be placed underneath the larger sheet, substantially as and for the purpose set forth.

In testimony of all which I have hereunto subscribed my name.

JOSEPH C. BONNER.
